UNITED STATES PATENT OFFICE.

ROGER DE POTTER, OF ANTWERP, BELGIUM.

MULTIPLE-EXPANSION STEAM TURBINE.

Application filed August 17, 1921. Serial No. 493,091.

To all whom it may concern:

Be it known that I, ROGER DE POTTER, a subject of the King of the Belgians, residing at Antwerp, Belgium, have invented 5 a certain Improved Multiple-Expansion Steam Turbine, of which the following is a specification.

The present invention relates to a multiple expansion steam-turbine and has for 10 its object to provide an improved type of turbine wherein the steam is utilized more advantageously than has been the case previously, mainly owing to an improved arrangement of buckets. The turbine forming 15 the subject matter of the present invention is also easier of construction than the existing types.

In order to facilitate the description of the invention, an embodiment of the same is, 20 by way of example only, illustrated by the accompanying drawings, wherein:

Figure 1 shows a front view of the improved turbine, with one of the lateral walls of the turbine casing partially removed in 25 order better to show the internal arrangement,

Figure 2 shows a longitudinal elevation of the said turbine, the upper cover of the casing having been partially removed.

Fig. 3 is a detached detail view of an obturator forming a part of the aforesaid turbine and its operating device, looking from above.

In the turbine forming the subject matter 35 of the present invention, the steam is admitted by means of one of the conical nozzles 10. These nozzles are divided in two portions 18 and 19 of gradually increasing cross section. A slide valve 15 sliding in 40 lateral grooves opens or closes successively the opening of the nozzles 18 and 19 according to the power required: This slide valve 15 is provided with a rack meshing with a tooth-wheel 16 operated by means of a hand 45 wheel 17. The same device for the admission of steam is employed when it is desired that the turbine should rotate in the reverse direction. The steam is admitted under the rotor 3 on a bucket wheel where it expands 50 by passing alternately into the upper and lower buckets (those of the bucket wheel 7 and those of a corresponding series of stationary buckets 8 provided on the inner periphery of the casing respectively). After 55 having passed through this first circle of buckets the steam passes by way of a pas-

sage 12 under the rotor to a second bucket wheel immediately adjacent the first and coaxial therewith, in which second wheel the steam expands further, to pass afterwards 60 in the same way through two further bucket wheels and from there to the condenser. Each wheel has side plates or discs 7' of a diameter slightly larger than that of the circle of the ridges separating the buckets. 65

According to theory, the maximum efficiency of a reaction turbine is obtained when the peripheral speed of the rotor is equal to the velocity of the steam: this condition is fulfilled in the present turbine owing to the 70 multiple circumferential expansions of the steam.

The 4 bucket-wheels and corresponding series of stationary buckets on the casing are all of the same diameter, but the second 75 is wider than the first, the third is wider than the second, and the fourth is wider than the third, the increase in width being proportional to the isothermic curves of the expansions of the steam. The lateral discs 80 or side plates 7' of the various bucket wheels are at their periphery provided with several U-shaped teeth 7" which engage themselves between the teeth 8" of the periphery of the lateral rings 8' separating the various 85 circles or series of stationary buckets of the casing from one another; the object of this arrangement is to prevent the escape of steam from one of the bucket wheels to the next. The buckets 7 of the rotor have a 90 semi-cylindrical shape, while the buckets 8 of the casing have the shape illustrated in Fig. 1, e. g., approximately corresponding to that of the buckets 7, but somewhat shallower, their walls being inclined from about 95 25° to 30° in relation to the outer casing.

The stationary buckets immediately preceding those which correspond to the admission of the steam are provided with a grate-like obturator constituted by two superposed plates or sheets of metal 9 and 9^a slotted or perforated like a grate; they slide one on the other and are moved by means of a rod 20 rotatably secured to each of the plates 9^a as shown at 20' and screw threaded 100 on a portion of its length, the screw threaded portion extending through a correspondingly threaded boss 21 of one of the sides of the outer casing of the turbine. The end of the rod 20 outside the turbine is fitted 110 with a handwheel 11 which when rotated causes the plates 9^a to slide against the

plates 9 in such a way as to close and open the openings or slots of the said plates 9.

As may be seen from Fig. 3, the set of two superposed plates forming the obturator 5 is provided for each of the expansions, the four sets of the embodiment shown being operated simultaneously by means of the single hand-wheel 11, through the medium of the rod 20.

10 The aforesaid obturator when closed acts as packing preventing the steam from flowing from the admission nozzles directly to the passage 12 leading to the second expansion stage, and directly from the passage 15 leading to such second expansion stage and to each subsequent expansion stage to the passage leading to the next expansion stage, the efficiency being then maximum, but when said obturator is partially open it allows some of the steam so to bypass, the efficiency being as a consequence correspondingly reduced. This obturator therefore provides a means of adjusting the efficiency according to needs.

25 The reversibility of the direction of rotation of the turbine is obtained by means of a conical nozzle arranged in a direction opposite to that adopted for the rotation in the forward direction; the steam passes 30 successively through the four bucket wheels in a manner identical for the two directions of rotation; a second grate-like obturator 9' also prevents any return of steam when the turbine is reversed. The bottom of the 35 buckets fitted with the grate-like obturators is open in order to allow the passage of the steam.

The turbine is very easy of construction as the rotor may be cast in one piece; the 40 same applies to the casing 4 provided with a reinforcing rib 5, whereas the construction of the turbines of the blade system is much longer and more complicated.

45 The axial thrust in the present turbine is practically nonexistent because of the way in which the steam acts on the circumference of the rotor, so that the use of thrust bearings is not required and the efficiency is therefore increased. A second outer-casing 50 6 encloses the machine thereby providing an air filled space or a space which may be filled with material suitable for preventing

any loss of heat, so that the condensation of the steam within the turbine is avoided. 13 and 14 are the steam inlet pipes for each 55 of the directions of rotation of the turbine respectively.

The turbine is constructed so as to be adapted to work with a condenser.

I claim:

1. In a multiple expansion reaction steam turbine, a plurality of rotary bucket-wheels of equal diameter each provided circumferentially with a plurality of semi-cylindrical buckets and of a width increasing proportionally to the isothermal curves of the expansions of the steam; in combination with a plurality of circumferential series of stationary buckets corresponding to the various bucket-wheels, secured to the inner periphery 65 of the turbine-casing, and each composed of a plurality of stationary buckets, equal in number to those of the corresponding bucket wheel and of a shape approximately corresponding to that of the last-named buckets 70 but somewhat shallower, substantially as described.

2. In a multiple expansion reaction steam turbine according to claim 1, an adjustable obturator fitted over the two stationary 80 buckets, immediately adjacent the two admission nozzles, of the lower sector of the turbine casing comprised between said two nozzles, said obturator consisting of two superposed plates able to slide in relation 85 to one another and having slots cut therein and so arranged that by said relative movement the slots in each plate may at will be caused to register with those of the other plate and to become gradually covered-up 90 until entirely obturated by the solid portions of said other plate; and suitable hand-operated means of known construction for effecting the adjustment of said two plates in relation to one another, substantially as 95 described.

In testimony thereof I signed hereunto my name in the presence of two subscribing witnesses.

ROGER DE POTTER.
